NECKTIE RACK

Robert L. Woerner, 823 Azalea, Houston, Tex. 77018

Filed Feb. 13, 1967, Ser. No. 5,794

Term of patent 7 years

Int. Cl. D6—01

U.S. Cl. D33—8

The dotted line showing of a necktie fragment in FIGURE 1 is for illustrative purposes only.

I claim:

The ornamental design for a necktie rack, as shown and described.
